UNITED STATES PATENT OFFICE

JAMES C. BAKER, OF LINCOLN, NEBRASKA, ASSIGNOR OF ONE-THIRD TO R. L. DAVIS, SR.,
AND ONE-THIRD TO A. J. OHLER, BOTH OF LINCOLN, NEBRASKA

WRENCH

Application filed April 30, 1929. Serial No. 359,291.

My invention relates to wrenches and its purpose is to provide a wrench which is more easily manipulated than the wrenches at present in use.

Another of my objects is the provision of a wrench which will have a "soft" but firm grip between the jaws regardless of whether it is used as a pipe wrench or for turning nuts.

10 Specifically, it is my object to provide a wrench having a handle member with a bar slidable thereon, the bar having the under jaw member pivotally secured thereto.

Having in view these objects and others 15 which will be pointed out in the following description, I will now refer to the drawings, in which

Figure 1 is a view partly in section showing one form of my wrench.

20 Figure 2 is a perspective view showing a pipe wrench embodying the novel features.

Figure 3 is a view in longitudinal section of a portion of the wrench, a portion of the handle member being broken away.

25 The handle member 10 terminates in the outer jaw member 11 which is integral with the handle member. The bar 12 surrounds the handle 10 and it is provided with an opening therethrough, the opening having a

30 width slightly greater than the width of the handle 10. The bar 12 has two fixed dogs 13^a and 13^b, the dog 13^a being forward of the dog 13^b. When the bar 12 is transverse to the handle 10 as shown in Figure 1, the

35 transverse distance between the two dogs is such that they will both bite into the front and rear edges of the handle member 10 to resist any sliding movement of the bar on the handle. A slight inclination of the bar 12 with reference to the handle 10 will afford

40 ample clearance between the two dogs so that the bar will slide readily on the handle. The bar 12 may be slidably moved away from the jaw member 11 by applying pressure at the rear end of the bar and in the direction of

45 the length of the handle. Likewise the bar may be moved toward the jaw member by applying pressure at the forward end of the bar toward the jaw member 11.

50 The importance of this construction is ob-

vious from the fact that the wrench is to be manipulated largely by the use of one hand only. It is possible therefore to grasp the handle and to use the thumb and forefinger respectively for sliding the bar along the handle in either direction. This makes it possible to adjust the wrench instantly without necessitating that the operator lay down some of his other tools in order to make his other hand free for use for the wrench.

The opening in the bar 12 extends to some distance forwardly of the dog 13^b. Within this portion of the opening is the under jaw member 14 which is pivotally secured at 15 to the bar 12. The jaw member has free pivotal movement within the bar 12 within the limits defined by the outer end of the bar 12 and by the edge of the handle member 10. The jaw member 14 is provided with a socket for receiving a coil spring 16 having a large headed pin 17 extending partly therethrough, the head of the pin bearing against the edge surface of the handle member 10. A second spring 18 is positioned between the jaw member 14 and the inner surface of the bar 12.

The spring pressed pin 17 urges the movable jaw 14 forwardly from the forward edge of the handle member 10 and this pressure is exerted against the spring 18 to compress the latter, the combined pressures of the springs urging the front end of the bar 12 inwardly from the fixed jaw 11 and binding the offset dogs 13^a and 13^b on the handle member 10.

In the construction shown in Figure 2 the parts are identical to those shown in Figure 1 with the exception of the additional tongue 19 which is a projection from the jaw member 14. This also is placed within convenient reach of the operator's fingers so that he may move the jaw member 14 outwardly when he is adjusting the wrench. This feature is particularly useful when the jaws are made to engage a pipe or other cylindrical object.

The front and rear edges of the handle member 10 may be smooth throughout but it has been found in practice that the material of which the wrench is made makes it desirable to provide additional holding

means. If the handle 10 is made from hard steel, the dogs will not have sufficient "grip" and they will slide along the edge of the handle member to release the hold of the jaws 13 on the nut or pipe. If the material of the handle is sufficiently soft to prevent the sliding of the dogs, the operative edge of the dog 13b is apt to bite into the edge of the handle member 10. This in itself would not be objectionable except for the fact that after the wrench has been in use for some time, a series of unequally spaced notches is produced in the edge of the handle and these notches will often be so placed as to make fine adjustment of the wrench impossible. I therefore provide corrugations or serrations 20 in the handle member, these corrugations or serrations being fine enough for close adjustment.

20 The two springs bearing against opposite sides of the jaw member to a certain extent act against each other but both cooperate in maintaining the slidable bar in latching position. Either spring, however, may be released by means of the thumb bearing against the jaw member itself or one of the fingers bearing against the tongue. As before stated, the wrench is designed to be manipulated by one hand and it is so designed that all of the operations could be carried out by a mechanic having only one arm. The tongue on the jaw member is particularly useful when the wrench is to be used as a pipe wrench since it enables the mechanic to adjust the jaw member to the most desirable inclination for seating the pipe between the jaws, at the same time sliding the bar so that the pipe is firmly grasped between the jaws.

40 Having thus described my invention in such full, clear, and exact terms that its construction and operation will be readily understood by others skilled in the art to which it pertains, what I claim as new and desire to secure by Letters Patent of the United States is:

1. A wrench comprising a handle member having a fixed jaw on its outer end, a slotted bar loosely mounted across the handle member, a fixed dog in the back of the bar opposite the rear edge of the handle member, a second fixed dog in the front of the bar opposite the forward edge of the handle member, said dogs being offset relative to the length of the bar and spaced apart a distance to free the bar for slidable adjustment lengthwise on the handle member when the front end of the bar is canted toward the fixed jaw and to bind the dogs against the respective rear and forward edges of the handle member when the bar is swung at its front end away from the fixed jaw, a movable jaw yieldably mounted on the forward end of the bar opposite the fixed jaw, the movable jaw having a shank pivotally mounted in the front end of the

bar and extending forwardly therefrom, a spring in the forward end of the bar between the latter and the forward edge of the shank for yieldably urging the movable jaw toward the forward edge of the handle member, and a spring pressed headed pin carried at the inner edge of the movable jaw for slidable engagement against the forward edge of the handle member to normally urge the movable jaw outwardly against said first spring and yieldably maintain the bar in locked position.

2. A wrench including a handle member and a fixed jaw member integral therewith, a slotted bar slidably positioned on said handle member, a pair of offset stationary dogs in said bar adapted to engage the respective forward and rear edges of said handle member, a movable jaw member pivotally secured to said bar within the slot thereof, a compression member between said movable jaw member and said handle member for normally maintaining said bar toward its transverse position relative to said handle member to thereby prevent said bar from sliding in a direction away from the fixed jaw member, and means projecting from said movable jaw member within convenient reach of the operator's fingers for moving said movable jaw member on its pivot to release said bar from latching engagement with said handle.

In testimony whereof I affix my signature.
JAMES C. BAKER.
